Specification for Design.

Patented Mar. 14, 1916.

Application filed January 3, 1916. Serial No. 70,045. Term of patent 14 years.

To all whom it may concern:

Be it known that I, EDGAR MOTT BOTTOME, a citizen of the United States, and residing at Moundsville, in the county of Marshall and State of West Virginia, have invented a certain new, original, and ornamental Design Applied to a Glass Vessel or Similar Article, of which the following is a specification, reference being had to the accompanying drawing, forming a part thereof, wherein a superficially-ornamented vessel is shown in elevation.

The design is shown applied to a tumbler of conventional form, the shape of which is not claimed.

I claim:—

The ornamental design applied to a glass vessel or similar article, substantially as shown.

EDGAR MOTT BOTTOME.
